UNITED STATES PATENT OFFICE.

HENRY G. BRENT, OF BRUNSWICK, MISSOURI.

BRIDLE.

SPECIFICATION forming part of Letters Patent No. 444,085, dated January 6, 1891.

Application filed July 10, 1890. Serial No. 358,318. (No model.)

To all whom it may concern:

Be it known that I, HENRY G. BRENT, a citizen of the United States, residing at Brunswick, in the county of Chariton and State of Missouri, have invented a new and useful Bridle, of which the following is a specification.

This invention relates to harness, and more particularly to that class thereof known as "bridles," and the object of the same is to effect improvements upon devices of this general character heretofore existing.

To this end the invention consists of a bridle constructed of a single piece of rope led from one side of the horse's head above, below, and around the same to the other side thereof, in a manner more fully described herein-after, and illustrated in the drawings, in which—

20 Figure 1 is a side elevation of this improved bridle, taken from the left side and showing it as applied to a horse's head, the latter being designated in outline by dotted lines. Fig. 2 is a similar elevation showing the 25 throat-latch as adjusted so as to be smaller and the attachment of the brow-band set farther to the rear. Fig. 3 is an enlarged elevation showing one-half of the bridle with the headstall adjusted to greater length.

30 Referring to the said drawings, the letter B designates a bit of any suitable construction, which is inserted in the horse's mouth, and L are links connected to the bit, as shown.

My improved bridle comprises a single piece 35 of rope, of any suitable size and material, arranged as follows: Starting from the point A at the left side of the head the rope passes through a loop O, over the crown of the head in a crown-piece coil C, around and through

40 a loop O at the other side of the head, thence down into the throat-latch T, thence back through a similar loop O at the left side of the head, through which the end A was also passed, thence up through a throat-knot K 45 at the left side of the head and again over the crown in the crown-piece coil C, through the twist W of the brow-band, down one side of the head in the headstall H, through one of the links L and back through the next

50 twist W, thence into the throat-knot K at the right side of the head, thence up through the brow-band knot D at the center of the brow-

band and into the twist W thereof, down the left side of the brow, forming the loop O, and returning loosely through the brow-band 55 throat-knot D, down the right side, forming the loop O at that side of the head and returning into and forming the other portion of the brow-band knot D, thence down the left side of the head into the throat-knot K, 60 thence through the twist W, along one cheek in the headstall H, through the other of the links L, and back through the next twist, thence over the crown in the crown-piece coil C to complete the throat-knot K at the right 65 side of the head, thence passing through the right loop O, and terminating at the point Z.

The throat-latch T of this bridle may be adjusted in length, as shown in Fig. 2, by drawing the point A through the loop O, which 70 draws upon the cord within the coil C and draws through the right loop O, thereby reducing the length of the throat-latch, the other end of which is fast in the left throat-knot K. The adjustment of the brow-band is effected 75 by throwing the brow-band knot D farther down or higher up upon the horse's nose. This movement is effected by loosening the double knot D and sliding the rope through the throat-knot and into or out of the half of 80 the twist W at the opposite side of the head. The adjustment of the length of the headstall is effected by loosening the throat-knots K and sliding the cord from the headstall into said knots or from the knots into the 85 headstall, as will be clearly understood.

A bridle constructed in accordance with the above description will possess adjustability sufficient to permit of its being applied to various-sized horses' heads, and yet it has no 90 buckles or snap-hooks.

The bridle is composed of a single piece of rope and is quite an ornament. The ends A and Z may be knotted and frayed out, as shown, if desired, and the rope may be composed of strands of different colors. The triple coil at the crown of the head and the twist over the brow, supplemented by the double knot, all assist in ornamenting this improved bridle, as well as serving their respective functions, as described above.

What I claim is—

1. The herein-described bridle, consisting of a single piece of rope comprising the crown-

piece coil C, an adjustable headstall H, leading from one of the strands of said crown-piece, throat-latch knots K, each comprising another strand of said crown-piece and the 5 return member of the headstall, and the throat-latch T, leading from said knots, substantially as and for the purpose set forth.

2. The herein-described bridle, consisting of a single piece of rope comprising a crown-piece coil C, an adjustable headstall H, leading from one of the strands of said crown-piece coil to the bit and returning to throat-latch knots K, a brow-band consisting of a 10 twist W, embracing said headstall and having loops O at its ends, the second strand of 15

said crown-piece coil C entering said side knots K, leading thence through said loops O, and forming the throat-latch T, and the headstall also entering said side knots and leading thence upwardly through a double knot 20 D and into the opposite sides of the brow-band twist W, the whole arranged and adapted for use substantially as hereinbefore set forth.

In testimony that I claim the foregoing as my own I have hereto affixed my signature 25 in presence of two witnesses.

HENRY G. BRENT.
